AEROSOL SPRAY HEAD

William C. Harris, Racine, Wis., assignor to S. C.
Johnson & Son, Inc., Racine, Wis.

Application December 22, 1949, Serial No. 6,767

Term of patent 14 years
(Cl. D62—2)

To all whom it may concern:

Be it known that I, William C. Harris, a citizen of the United States residing at Racine, in the county of Racine and State of Wisconsin, have invented a new, original, and ornamental Design for an Aerosol Spray Head, of which the following is a specification, reference being had to the accompanying drawing, forming part thereof.

Figure 1 is a perspective view of an aerosol spray head, showing my new design.

Figure 2 is a front elevational view of the aerosol spray head shown in Figure 1.

Figure 3 is a side elevational view of the aerosol spray head shown in Figure 1.

Figure 4 is a top plan view of the aerosol spray head shown in Figure 1.

The side not shown is substantially the same as the one shown in Figure 3.

I claim:

The ornamental design for an aerosol spray head, as shown and described.

WILLIAM C. HARRIS.
